UNITED STATES PATENT OFFICE

HAROLD L. HERZFELDER, OF NEW YORK, N. Y., AND MARCUS HARRIS, OF NEWARK, NEW JERSEY; SAID HARRIS ASSIGNOR TO SAID HERZFELDER

DESIGN FOR A LAMP OR SIMILAR ARTICLE

Application filed April 29, 1933. Serial No. 47,940. Term of patent 3½ years.

To all whom it may concern.

Be it known that we, HAROLD L. HERZFELDER and MARCUS HARRIS, both citizens of the United States of America, and residing at 145 West 86th Street, New York, New York, and 31 Eckert Avenue, Newark, New Jersey, respectively, have invented a new, original, and ornamental Design for a Lamp or Similar Article, of which the following is a specification, reference being had to the accompanying drawing, forming a part hereof.

Fig. 1 is a perspective view of a lamp showing our new design.

Fig. 2 is an edge view thereof.

We claim:

The ornamental design for a lamp or similar article as shown.

In testimony whereof we have signed this specification.

HAROLD L. HERZFELDER.
MARCUS HARRIS.
